CLAIM

The ornamental design for a cleaning implement, as shown and described.

DESCRIPTION

FIG. 1 is a perspective view of a cleaning implement, showing our new design;

FIG. 2 is a side elevational view with the opposite side being a mirror image thereof;

FIG. 3 is a top view thereof;

FIG. 4 is a front elevational view thereof;

FIG. 5 is a back elevational view thereof; and,

FIG. 6 is a bottom view thereof.

The handle shown in broken lines in FIGS. 1-5 is for illustrative purposes only and forms no part of the claimed design.
